UNITED STATES PATENT OFFICE.

WALTER W. PHILLIPS, OF PHILADELPHIA, PENNSYLVANIA.

FEED-WATER HEATER.

Application filed July 5, 1923. Serial No. 649,641.

My invention relates to new and useful improvements in a feed water heater, which is particularly adapted for use in marine boilers although not especially confined thereto and has for its primary object the provision of means to flood the heater in case the regular circulation of water therethrough should cease from any cause whatever.

Another object of the invention is to provide a feed water heater for installation in the flame course of a fire tube boiler having flood line connections with the water space to automatically fill the heater with water from the boiler should the ordinary circulation through said heater be shut off.

A further object of this invention is to provide unique means for supporting the heater within the flame path and more particularly within the combustion chamber.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings forming a part of this application, in which:—

Fig. 1 is a sectional end view of a boiler, of the Scotch type, illustrating the use of my improved automatic feed water heater therein.

Fig. 2 is a sectional side elevation thereof.

Fig. 3 is a fragmentary sectional plan view of the same.

Fig. 4 is a fragmentary front elevation of the boiler showing the relative positions of the flood lines used with this type of heater.

Fig. 5 is an enlarged fragmentary sectional view illustrating the details of construction of one of the headers or manifolds and its mode of connection with the boiler.

Fig. 6 is an enlarged sectional side elevation of one of the brackets.

Fig. 7 is a front elevation thereof.

Fig. 8 is a plan view of the same.

Fig. 9 is a broken end elevation of a modified form of my invention on a reduced scale particularly adapted for use in boilers of the Legg type.

Fig. 10 is a fragmentary sectional side elevation of the same.

Fig. 11 is a fragmentary sectional plan view thereof.

Fig. 12 is an enlarged sectional view of the connecting pipe at the line 12—12 of Fig. 11.

In carrying out my invention as embodied in Figs. 1 to 8 inclusive, 2 represents a marine or fire tube boiler of the Scotch type having one or more furnaces 3 leading to the combustion chamber 4 from which lead the return tubes 5 and having a water space 6 about the furnaces, return tubes and the combustion chambers.

Within the combustion chamber is located the feed water heater represented as a whole by the numeral 6. This heater preferably comprises two headers or manifolds 7 and 8 each having an opening 9 one of which acts as an inlet and the other as an outlet during operation, but both acting as inlets for the flood water should circulation cease at any time. The interiors of these headers or manifolds are divided into a plurality of chambers here shown as two in number and denoted by the reference numerals 10 and 11, said chambers being separated from each other by baffles 12. Between the headers or manifolds are arranged a plurality of tubes 13 all of which are secured in place by rolling a flange or bead 14 on the ends thereof within the headers, as plainly shown in Fig. 5, and in the walls of the headers directly opposite the walls through which the tubes pass and directly opposite said tubes are formed a plurality of access holes 15 each normally closed by a screw threaded plug 16 which may be readily removed for rolling the flange or bead on the tubes or to permit the insertion of a tool for cutting away said

flanges in order that all or any one of the tubes may be removed for replacement purposes.

In the holes 9 in each of the headers are threaded the pipes 17 and 18 the former acting as the inlet or intake pipe from a pump or other equivalent means while the latter acts as the outlet from the heaters and forms a communication with the boiler inlet pipe 18', Fig. 1. These pipes pass through the two adjacent walls of the boiler and combustion chamber as plainly shown in Fig. 5 and are supported on the outside of the boiler by suitable brackets 19. As shown in Figs. 6, 7 and 8, each bracket comprises a body member 20 having an arcuate channel 21 to fit about a pipe with outwardly pro-

jecting flanges 22 and a depending lug 23 having a hole 24 therethrough for the passage of a bolt 25, preferably a stud, which has threaded connection with the end wall 3 of the boiler. Coacting with the body member is a complementary or cap member 26 also having an arcuate channel 27 for registration with the pipe and provided with outwardly projecting flanges 28 adapted to 16 overlie the flanges 22 of the body member and through these flanges pass suitable securing means 29 such as bolts or their equivalent.

Surrounding each of the pipes 17 and 18 15 preferably concentric therewith and bridging the space between the end wall of the boiler and the adjacent wall of the combustion chamber is a casing 30 the ends of which are fixed in the walls of the boiler and combustion chamber as by rolling flanges on the ends of said casing or in any other suitable manner to provide a secure joint. The space between the casing 30 and the pipe which it surrounds is filled with asbestos 31 or other 20 suitable equivalent heat resisting packing.

To the inlet pipe 17 is connected a flood line 32 which enters the boiler below the normal water level therein and preferably in a horizontal line with said inlet pipe or 30 with the point of entrance of said inlet pipe through the boiler to the heater, thus forming a communication between the water compartment of the boiler and the inlet pipe to the heater. In this flood line is 35 located a check valve 33 herein conventionally shown since the details of construction of such valves are well known and any of those on the market may be used. This check valve is adapted to remain closed so long as the necessary pressure is maintained to 40 cause a circulation of feed water through the heater but will open as soon as such pressure is reduced so as to permit water from the boiler to flow directly into the intake and then into the heater. In order to close the 45 flood line, as for instance when repairs are to be made or when the device is not in use, I prefer to insert a shut off valve 34 in said flood line, such valve being also conventionally shown as any standard valve may be used.

Connected with the outlet pipe 18 is another flood line 35 similar in all details to the one above described and forming a communication with the water compartment of the boiler and said outlet pipe 18 is preferably arranged in a horizontal line to the point of passage of the outlet pipe through the boiler end wall. This flood line also includes a check valve 36 and a shut off valve 37 actuating in the same manner and for the same purposes as described with relation to the valves 33 and 34.

From the foregoing description it will be 55 seen that when the feed water is properly

circulating it will pass through the intake pipe 17 into the smaller compartment 10 of the header or manifold 8, then through the tubes 13 connected with said compartment into the larger compartment of the header 70 or manifold 7 and from said larger compartment through the other tubes connected therewith to the larger compartment of the header 8 and then from this last named compartment through the other tubes connected therewith to the smaller compartment of the header 7 thence through the outlet pipe 18 to the water compartment of the boiler at 75 relatively high temperature.

If, for any cause whatever, the circulation of the feed water should cease the pressure holding the check valves 33 and 36 in a closed position will be eliminated and the pressure of the water in the boiler will cause said check valves to open so that this water will flow through the flood lines thence through the pipes 17 and 18 into the heater so that it will be filled with water and will not burn out and as soon as this water becomes heated a circulation will be set up through the flood lines, the inlet and outlet pipes so as to maintain the heater at a temperature sufficiently low to prevent damage thereto. Should the flood line, or any part thereof, become damaged at any time the 80 shut off valves 34 and 37 may be closed and the circulation through the pipes 17 and 18 being stopped the necessary repairs may be 85 readily made.

As the inlet and outlet pipes 17 and 18 respectively are not fixed to the boiler or combustion chamber said pipes may expand and contract without injury to the parts and the filler 31 will act as an effective packing to prevent the escape of products of combustion.

In Figs. 9 to 12 inclusive, I have shown a slightly modified form of my invention which is particularly adapted for use with that type known as Legg boilers wherein two heater units are employed to give substantially the same heating surface as in the form above described while providing structural units small enough to be inserted through the man-hole.

In this form of the invention 40 represents the boiler provided with a combustion chamber 41 access to which is obtained through a man-hole 42 between adjacent end walls of the boiler and combustion chamber.

In the combustion chamber is located the heater 43 comprising a plurality of units, here shown as two in number, and represented by the reference numerals 44 and 45. Each unit comprises two headers or manifolds 46 and 47 to which are attached the tubes 48 in the same manner as described with relation to the single unit heater and access to the ends of said tubes is obtained 120 125 130

through holes in the headers which are normally closed by the screw plugs 49. The upper headers of the units are in communication or connected by a pipe 50 having right 5 and left hand threads with an intermediate polygonal wrench hold 51 whereby said pipe may be screwed in place and said upper headers are divided into two compartments by a baffle 52.

10 To one of the upper headers of one of the units, as 44, is connected an inlet pipe 53 so that the circulation of water will pass through said inlet pipe into one of the compartments of the upper header, then through 15 the tubes communicating with said compartment to the lower header of said unit, then through the other tubes of the same unit to the other compartment of the upper header, then through the pipe 50 to the upper header of the other unit through which it circulates in the same manner as above described and thence through the outlet pipe 54 connected with the last named unit to the water compartment of the boiler. The inlet and 20 outlet pipes 53 and 54 respectively are mounted in the same manner as described relative to that form illustrated in Fig. 1 and are preferably both connected with the upper headers of their respective heater units and are therefore on a substantially horizontal straight line. To the water compartment of the boiler below the normal water level and to the inlet and outlet pipes are connected separate flood lines 55 25 and 56 which are identical in all details to the flood lines before described. Said flood lines enter the water compartment of the boiler in the same horizontal line as the outlet pipes.

30 In case the feed water circulation should cease and the pressure on one side of the check valves thus be relieved the pressure of the boiler water will open said check valves and permit said boiler water to flood 35 each of the heater units so as to prevent the parts of the heater from being damaged by the heat of the fire in the boiler furnace.

Of course I do not wish to be limited to 40 the exact details of construction as herein shown as these may be varied within the lim-

its of the appended claims without departing from the spirit of my invention.

Having thus fully described my invention, 45 what I claim as new and useful is:

1. The combination with a boiler including a combustion chamber and the surrounding water compartment, of a heater located within the combustion chamber and having communicating chambers of different capacities, an inlet pipe leading from a source of feed water supply to one chamber of the heater, an outlet pipe leading from another chamber of said heater to the water compartment of the boiler, flood lines forming 50 communications between the water compartment of the boiler below the normal water level thereof and said inlet and outlet pipes and check valves controlled by the water pressures to maintain the flood lines 55 in closed condition during circulation of the feed water and to automatically open said flood lines upon reduction of pressure in said feed water circulation to permit boiler water to flood the heater in order to prevent damage to said heater due to heat in the combustion chamber.

2. A device of the character described comprising, in combination, a boiler having a combustion chamber and a surrounding water compartment, a feed water heater within the combustion chamber, and having serially connected chambers of different capacities, the smaller ones of which have ports therein, a feed water circulating system including pipes communicating with the smaller chambers of the heater through said ports thereof, a pipe connected to each of the above mentioned pipes of the circulating system and forming communication with the water compartment of the boiler below the normal low water level, and check valves in the last mentioned pipes so positioned as to be held closed by predetermined pressure of the water in the heater and adapted to be 85 opened upon diminution of said water pressure whereby water will flow directly from the boiler into the circulating system adjacent the feed water heater.

In testimony whereof, I have hereunto 90 affixed my signature.

WALTER W. PHILLIPS.
